Primary Examiner — Wan Laymon*Assistant Examiner* — Clint A Samuel(74) *Attorney, Agent, or Firm* — Price Heneveld LLP(57) **CLAIM**

The ornamental design for a dental bite block, as shown and described.

DESCRIPTION

FIG. 1 is a front perspective view of a dental bite block according to my design;

FIG. 2 is a right elevational view thereof;

FIG. 3 is a left elevational view thereof;

FIG. 4 is a top elevational view thereof;

FIG. 5 is a front elevational view thereof;

FIG. 6 is a bottom elevational view thereof; and,

FIG. 7 is a rear elevational view thereof.

The broken line showing of various features is for the purpose of illustrating unclaimed portions of the dental bite block and forms no part of the claimed design.

1 Claim, 2 Drawing Sheets# US D782,048 S
